SPROCKET SPINNER HUB

Viktor Schreckengost, Cleveland Heights, Ohio, assignor
to The Murray Ohio Manufacturing Co., Nashville,
Tenn., a corporation of Ohio

Filed Nov. 20, 1962, Ser. No. 72,556

Term of patent 14 years

(Cl. D90—17)

FIGURE 1 is a front elevational view of a sprocket spinner hub showing my new design;

FIGURE 2 is a rear elevational view thereof;

FIGURE 3 is a bottom plan view thereof; and

FIGURE 4 is a sectional view taken along line 4—4 of FIGURE 1.

I claim:

The ornamental design for a sprocket spinner hub, substantially as shown.
